UNITED STATES PATENT OFFICE.

LYNDON CONSTANTINE PALMER, OF BUFFALO, NEW YORK, ASSIGNOR TO F. N. BURT COMPANY, LIMITED, OF BUFFALO, NEW YORK, A CORPORATION OF ONTARIO, CANADA.

LABELING-MACHINE.

1,193,292.

Specification of Letters Patent. Patented Aug. 1, 1916.

Application filed December 9, 1911. Serial No. 664,774.

To all whom it may concern:

Be it known that I, LYNDON C. PALMER, a citizen of the United States, residing at Buffalo, in the county of Erie and State 5 of New York, have invented certain new and useful Improvements in Labeling-Machines, of which the following is a full, clear, and exact description, such as will enable others skilled in the art to which it 10 appertains to make and use the same.

This invention relates to mechanism for applying labels to articles, and more especially to devices for securing labels to boxes.

15 One object of the invention is the provision of mechanism for efficiently pasting a label to a box.

Another object of the invention is the provision of a comparatively simple mechanism 20 for applying labels to the inside surface of a box, and especially to the inside surface of a large number of boxes in a short space of time.

Another object is to provide means for 25 effectively applying labels to boxes so that they shall present a smooth and even surface.

Still another object is the provision of means whereby the label is symmetrically 30 arranged with respect to the box.

Another object is to provide a device in which the adhesive is accurately and economically applied to the parts to be glued 35 without waste and without gumming up adjacent parts.

Another object is the simple and efficient removal of the labeled boxes from the machine.

Other objects will be in part obvious and 40 in part pointed out hereinafter.

The invention accordingly consists in the features of construction, combinations of elements and arrangement of parts which 45 will be exemplified in the construction hereinafter set forth, and the scope of the application of which will be indicated in the following claims.

In the drawings, wherein is shown one 50 of the possible embodiments of the invention, Figure 1 is a rear elevation of the machine; Fig. 2 is a plan view thereof; Fig. 3 is a horizontal section taken below the bed plate, parts being omitted for the

sake of clearness; Fig. 4 is an enlarged horizontal section, partly broken away, showing the box carrier and operating mechanism; Fig. 5 is a vertical central section through Fig. 4; Fig. 6 is a vertical sectional detail view showing one of the pressers and operating mechanism; Fig. 7 is a detail 60 side elevation of the cross head and glue pad carrier; Figs. 8, 9, 10 and 11 are detail views of the glue pad carrier; Fig. 12 shows the operating cam for the cross head; Fig. 13 is a detail plan of the label magazine, 65 box feeding picker mechanism and ejecting mechanism; Fig. 14 is a detail elevation of the ejecting mechanism; Fig. 15 is a detail elevation of the picker mechanism and box conveyer, partly in section; Fig. 16 is 70 a front elevation of the picker; Fig. 17 is a horizontal sectional detail of the picker; Fig. 18 is a plan of the box conveyer mechanism; Fig. 19 is a sectional elevation of the box conveyer mechanism; Fig. 20 is a detail 75 elevation showing a box rest and the retaining means; Fig. 21 is a transverse section of a box rest; Figs. 22 and 23 are plan and side elevations, respectively, of the glue transferring mechanism; Fig. 24 is a sec- 80 tional detail through the glue transferring mechanism; Figs. 25 and 26 are elevation and plan views, respectively, of the glue tank and glue feed rollers; Fig. 27 is an elevation of the label follower or hammer 85 mechanism, partly in section; Figs. 28 and 29 are details of the label follower or hammer, partly in section; Fig. 30 shows the cam operating mechanism for the follower or hammer; Fig. 31 is a sectional detail 90 showing the arrangement of the device for governing the descent of the glue pad; Figs. 32 and 33 are details of said device; Figs. 34 and 35 are plan and elevation views, respectively, of a modification, one of the de- 95 tent fingers being broken away and turned from correct position for illustrative purposes only.

The general arrangement of the preferred embodiment of the invention as illustrated in the accompanying drawings comprises a movable carrier for a plurality of boxes, a box supplying device by means of which boxes are fed to a certain position adjacent the box carrier mechanism operating 100 to transfer the boxes from the supply device.

2
to the carrier, a gluing mechanism disposed adjacent the path of movement of the box on the carrier, label supporting and manipulating devices also adjacent the path of the box on the carrier and adapted at proper times to coöperate therewith, and mechanism for stripping the labeled boxes from the carrier and throwing them to one side.

5 The detailed construction of the mechanism referred to may, of course, be varied, and their association in different relationships may be indicated by general or specific terms within the spirit of the results accomplished by such associated elements without 10 departing from the invention.

15 Referring now more specifically to the accompanying drawings, the numeral 1 represents a stand of sufficient height to dispose the operating mechanism at a convenient 20 height for manipulation.

25 2 indicates an elevated horizontal bed plate having supporting upright standards 3 and 4 securely fastened to the upper surface of the stand. Projecting upwardly from an intermediate portion of the bed plate is a cylindrical bearing 5 supporting thereabove a fixed platform 6 secured thereto and adapted to serve as a support for some 30 of the elements of the machine. A preferably circular rotary box supporting and carrying table or disk 7 surrounds the bearing, the periphery of said disk being flanged, as at 8, and said flange bearing on a complementary upstanding flange 9 on the bed plate, providing a space between the bed plate and the body of the rotary disk to accommodate operating connections for the disk. Fastened to the bottom of the disk within the space above referred to is a 35 Geneva gear wheel 10 comprising the radial slots 11 and the curved peripheral portions 12. Said gear wheel has an upstanding hub portion 13 and rests upon the bed plate, and is secured to and supports the box carrier disk with the bottom portion of its flange 8 closely adjacent the flange 9 on the bed plate. Wear plates are interposed between the hub 13 and the bearing 5. 40 14 indicates a wheel having a pin adapted to engage the slots 11 of the Geneva gear wheel, the wheel 14 having a hub or circular peripheral portion 15 adapted to engage the curved portions 12 of the Geneva gear and lock said gear against movement except 45 when the pin coöperates with the slot thereof. Provision is made for the movement of the Geneva gear by cutting away a portion of the pin wheel, as shown at 16.

50 With the above described construction it will be evident that when the pin wheel is rotated the Geneva gear will be rotated intermittently, step by step, for a certain amount, and between the periods of its movements will be locked by the hub of the pin wheel, the concentric portion of the hub

50 of which at that time engages the curved portion of the gear. In the present instance the Geneva gear is rotated one-twelfth of a revolution for every revolution of the pin wheel in order to comport with the operations upon the box and provide idle points, as will hereinafter appear.

55 The intermittently rotating carrier plate serves as a means for supporting and carrying a series of boxes successively into positions adjacent mechanisms, the operation of which results in affixing labels to the boxes and in stripping or ejecting the labeled boxes from the carrier. In the present embodiment the boxes to be labeled are sup-

60 plied to a conveyer or box-supply device located at one side of the carrier plate. The construction of this box-supply device may be of any efficient form, but is preferably similar in general details to that disclosed in

65 applicant's Patent No. 1,019,351, March 5, 1912, comprising an endless belt 17. In the present instance, however, it is designed to label boxes on the inside thereof instead of

70 on the outside, as described in the aforesaid application, and accordingly the attendant places the boxes open side up upon the conveyer belt 17, which latter conveys them successively into a certain or predetermined position alongside the carrier plate, whence

75 they are drawn or slid onto box rests on said plate, as will hereinafter appear. Preferably the conveyer frame comprises a trough on the bottom plate 17' of which the upper

80 ply of belt 17 is supported and moves, and one of the belt supporting rollers is journaled in a bracket adjustably fixed to said trough. The upper ply of the belt is substantially in horizontal alignment with a box retainer and above the plane of box rests

85 hereinafter described.

90 Before describing in detail the several devices employed in labeling the boxes, it will be conducive to a clearer understanding of the operation of the machine to describe at this point the character and arrangement of the main driving mechanism.

95 The numeral 18 indicates a main horizontal driving shaft journaled in brackets 19 and 20 secured to the stand, and located between the stand and the bed plate. Standards 21 and 22 disposed centrally longitudinally of the stand support a horizontal cam

100 shaft 23, which is continuously driven from shaft 18 by intermeshing toothed wheels 24 and 25. The devices employed in gluing, labeling and ejecting are mainly driven from

105 said cam shaft as will hereinafter appear. Near one end of the main driving shaft 18 is fastened a bevel gear 26, meshing with a similar gear 27 on a counter shaft 28, this latter shaft carrying at its opposite end two sprocket wheels 29 and 30, the former designed to drive the glue delivery devices of the glue reservoir through chain 31, and the

latter the conveyer belt 17 through chain 32. Mounted at one end of the cam shaft 23 is a bevel gear 33, meshing with a similar wheel 34 on a vertical shaft 35 which carries at its upper end the pin wheel 14 of the Geneva driving gear.

35' indicates a belt pulley adapted to be continuously driven from any suitable source of power, and 36 represents a clutch device of any efficient construction and adapted to be operated through rods 37, rock shaft 38, and hand lever 39, the latter being disposed in convenient position for manipulation by the attendant. As the shaft 18 rotates, continuous rotation of shafts 23 and 28 is effected, the Geneva gear is operated to rotate the carrier 7 step by step, and the other elements of the machine are operated in the manner intended, as will clearly appear hereinafter.

Removably and adjustably mounted upon the carrier plate and near the periphery thereof is a series of box supports or rests each comprising a base portion 40 adjustable 25 relative to the plate, and a box carrying or supporting portion 41 removably connected to the base portion, preferably by means of alining pins 42 projecting upwardly from the base portion and received in guiding 30 openings in the bottom of the supporting portion of the rest, the supporting portion being secured to the base portion by means of a screw 43 or other suitable fastening device, permitting the supporting portion to 35 be removed when desired. In order to provide for the accurate positioning of the boxes with their upstanding flanges on the rests, the latter are provided with peripheral projections in the shape of flanges 44, 45 40 and 46, and, as by the present embodiment provision is made for labeling substantially rectangular boxes, three sides of the rest are provided with said flanges, angularly arranged relative to each other, the fourth 45 side being left free and providing an intervening opening, except as will hereinafter appear, so that a box may be slid or transferred from the conveyer belt 17 onto the box rest, on which it will be guided and positioned by said flanges. In order that the boxes shall be prevented from substantial displacement in a plane perpendicular to that of the rest, the opposite flanges 44 and 45 are provided with overhanging portions 50 47 which span the thickness of the box flanges. The inner flange 46 serves as a stop to limit the radial position of the box relative to the rest and the carrier on which it is supported, and this stop terminates below 55 the top of the box flange and is unprovided with an overhanging flange, for purposes which will hereinafter appear. The flanges of the rest are accordingly spaced from each other peripherally of the rest to a sufficient extent to permit a box to be drawn from the

conveyer into the chamber of the rest formed by the flanges aforesaid. A box having been positioned on a rest will, as the rest moves, be carried to different positions where labeling operations take place, and 70 in order that the box may remain securely in position on the rest as the rest moves and without liability of substantial movement relative thereto, means are provided for obstructing or substantially closing the intervening opening between the flanges of the rest, said means in the preferred embodiment comprising a stop or latch 48 pivotally connected to the rest as by a pin 49 and adapted to be moved into and out of position in alinement with that path of movement of a box on entering or leaving the chamber of the rest. Said latch is provided with a tail portion 50, preferably trailing with respect to the direction of movement 80 of the rest, carrying an anti-friction roller 51 adapted to contact and be guided, and at certain places moved, by a cam track 52 located adjacent the path of movement of the rests, as will be described hereinafter. 90 It will be observed from the construction hereinafter set forth that as the rest travels the stops 48 are at times moved across the intervening opening, and again uncover the same, thus having an oscillatory movement, 95 and in order that this movement shall not be so free as to be accidentally accomplished the stop is preferably arranged to resist accidental movement, as by setting up the screw pivot pin 49 so as to cause the stop 100 to press against the rest, the friction so established being sufficient to temporarily retain it in position across or below the intervening opening referred to until positively moved. It will be noted that when 105 the latch is in position intersecting the path of movement of the box, said box is held substantially in immovable position relative to the rest, so that when the box is presented to the label operating mechanism or any 110 element thereof having co-operative relationship with the box, accurate and exact relative arrangement is assured.

The mechanism for transferring the boxes from the conveyer to the box rests comprises a picker involving a reciprocatory picker bar 53 having flanges 54 slidably supported on a bracket 55 secured to the central platform 6. Said picker bar is reciprocated through the instrumentality of an adjustable connecting rod 56 pivoted to an arm 57 secured to a rock shaft 58, the latter provided with a gear 59 meshing with a rack 60 on the label magazine, this manner of operating connection being preferred in the interest of simplicity of parts, as the operations of the picker readily synchronize with those of the label magazine, as will appear. The picker bar is provided with a movable picker finger pivoted on the end 120 125 130

of the bar; with its end portion adapted to occupy a position in alinement with the boxes as they are fed into position by the conveyer mechanism. In the present embodiment a bracket 61 is securely fastened to the end of the picker bar and projects laterally and downwardly therefrom in alinement with the path of the boxes as they pass to the rest from the belt 17, and the picker finger comprises a plate 62 pivoted to the bracket, said plate being of a sufficient width to substantially span a box to be fed. The finger or plate 62 when in feeding position depends across the path of the boxes, and as the picker bar reciprocates the finger engages the outside wall of the box which has been conveyed to proper position by the belt 17, and moves or slides the box from the belt to the box rest, and into the chamber thereof through the intervening opening. The conveyer mechanism is spaced slightly from the rests, the space being bridged by a short projecting plate 63, the outer end of which closely approximates the rest, so that a convenient way from the belt to the rest is provided. As the finger passes back to feed a new box, provision is made for raising the finger out of contact with the new box comprising a pivoted switch 64 which guides a pin 65 carried on the lower lateral portion of the finger. In retreating, the pin 65 follows the inclined track formed by the switch 64 and drops from the track into feeding position. On forward movement of the pin 65, it passes beneath the switch 64, as will readily appear. Provision is made for positively causing the finger to assume proper position in alinement with the box to be fed, comprising a spring 66, one end of which is attached to the finger and the other end to the bracket 61, the spring being disposed across the pivoted joint connecting the finger and bracket. Should the picker finger 62 encounter any obstruction in its feeding movement, or should the box to be fed for any reason offer undue resistance, provision is made to enable the finger to yield rather than cause undue strain of the working parts or the crushing of the box. To this end the bracket 61 is provided with a projecting arm 67 carrying a pin 68, encircled by a spring 69, one end of which spring bears against a plate 70 mounted to rock or rotate on the pin 68, the spring 69 pressing the plate 70 against the arm 67 with a yielding pressure depending upon the adjustment of the nut 71. Preferably, the friction thus established between the arm and plate is accentuated by providing said parts, one with a beveled tooth 72 and the other with a recess 73 having inclined walls. The plate 70 has its lower end 74 terminating in position to serve as a stop to determine the feeding position of the picker finger, the spring 66 serving to move the

finger to position against such stop. As the picker finger moves to feed a box, the friction clutch comprised in the plates 67 and 70 and the spring 69 will yield should undue resistance be encountered, and the spring 66, by reason of its location across the pivotal point, will preserve the new position of the finger until returned to position by hand. Thus the co-operating clutch elements described provide a friction clutch device between the finger and the bar to yieldingly oppose movement of the finger relative to the bar in one direction, and the spring connected to the bar and finger opposes relative movement of the finger in the opposite direction and returns the finger to normal feeding position.

In order that the boxes may be readily fed to the carrier, the corner of the guiding wall of the belt conveyer trough is rounded as at 75 to ease a box into the guideway leading to the carrier, and in order to preserve the alinement of the walls of the box with those of said way, a stop or yielding guiding member is employed comprising a roller 76 in the guideway leading to the carrier, this roller being carried by a leaf spring 77 adjustably fastened to the conveyer frame. The periphery of the roller 76 intersects the path of the boxes in the guideway leading to the carrier, extending below the tops of the flanges thereof, and the roller is so positioned that as the boxes arrive in feeding position their trailing walls are positioned substantially opposite the roller, which prevents their rotation in a horizontal plane and which yet yields to permit their feed by the picker, the plane of rotation of the roller being transverse to movement of boxes by the belt 17.

A box having been fed onto the support, the Geneva mechanism is operated and the carrier rotated to convey the box to a position in which glue is applied thereto. In the present embodiment the boxes will be held at rest twice between the position of the picker and that of the glue-applying device, such idle positions being provided in order that the boxes may be inspected and any defaced boxes removed therefrom.

It will be understood that when a box has been fed from the conveyer belt to a rest, it is carried by the latter to a position in which glue is applied thereto; thence to a position where labels are applied to the glued surface; thence beneath presses, and thence to a device which strips or ejects the box from the rest. In order that the box shall be efficiently held in position on the rest when gluing, labeling and pressing, the cam track 52 hereinbefore mentioned is provided. This track comprises a narrow thin plate 52, fixed to the bed plate by brackets 78, and disposed above and just inside the periphery of the carrier plate 7. An in-

clined end portion 79 of the track rises from the surfaces of the carrier, and as the rest moves from pressing position to that of ejecting, the roller 51 which has been following the plane surface of the carrier moves up the incline 79, thus causing the stop 48 to move below the surface of the rest, so that the ejector may push or slide the box off the rest. The rest next moves to picking position, the stop maintaining its lowered position until the new box has been placed on the rest. As the rest moves from picking position the roller 51 encounters a cam surface 80 of an upper guiding track 81, similar in construction to track 52, the roller being directed down, the stop 48 being positively lifted to position across the intervening opening. Thereafter and until the box leaves the last pressing station, the stop 48 remains in box engaging position. The track 81 preferably extends sufficiently around the carrier to positively maintain the stop 48 in box engaging position until the label has been applied, although in the present embodiment it is continued further.

The bed plate 2 extends sufficiently to one side of the carrier plate to support a glue reservoir comprising a tank 82 having upstanding plates 83 supporting glue supply and delivery rollers of the general character disclosed in the patent hereinbefore referred to. Brackets 84 secured to the bed plate support, at one end, guide rods 85 extending across the path of the box rests, the other ends being supported by brackets 86 secured to the central stationary platform 6. A glue-applying roller 87 is guided between the bars of said rods and carries glue from the delivery roller to a glue pad 88 supported in line with a stationary position assumed by the box rests. The manner of supporting the guide rods and the guiding devices whereby the glue-applying roller is moved from the glue supply to the pad are generally similar to those described in the aforesaid patent. The glue pad 88 comprises preferably a rubber block covered with canvas and held in a plate 89 adjustably mounted in another plate 90 resiliently supported upon a cross head 91 adapted to reciprocate toward and from the plane of the carrier in order to deliver glue to a box supported on a rest beneath the same. In the present embodiment the cross head 91 is provided with a bracket comprising a block 92 through which pass guiding and supporting pins 93 provided with stop nuts 94 at their upper ends, the lower ends of the rods being attached to the plate 90, to the bottom of which latter are fastened under-cut guide plates 95 forming a dove-tailed channel adapted to be slidingly engaged by a projecting portion 96 of the plate carrying the pad. The plate 90 is provided with depend-

ing brackets 97 through which pass adjusting screws 98 which abut the ends of the pad-carrying plate so as to permit the transverse adjustment of the pad relative to its support and also relative to the box rests. Between the plate 90 and the block 92 and surrounding the pins 93, resilient means, as springs 99, are interposed, and as the cross head is operated the glue pad descends toward the box rests, being adapted to enter between the flanges of the box therebeneath and glue the inner bottom face or surface thereof with a yielding pressure, as will now be apparent.

In order to prevent the pad from applying glue to the surface of the rest should no box be in position thereon, a rock shaft 100 is journaled on the side of the block 92 and centrally connected by an arm 101 and link 102 to the plate 90. An arm 103 on the end 80 of the shaft 100 has a forked end engaging a pin 104 of a square detent rod 105 mounted to reciprocate in the block. Thus the springs 99 maintain the rod 105 in elevated position. Supported on the central platform 6 is a base bracket 106, supporting a sliding rod 107, preferably of rectangular cross section, having a pin 108, engaging a slot 109 in one end of a lever 110 pivoted at its other end to an arm of the bracket 95 106 and carrying a cam in the shape of an anti-friction roller 111, located in a horizontal plane on a line with the wall of a box when in position on a rest, said roller being moved by a spring 112 to intersect the path 100 of the box wall, and adapted to be pressed away from the rest by said wall as the box passes. Preferably, the rod 107 has a reduced portion comprising a stem 300 forming a shoulder 301, and the spring 112 encircles the stem 300, and lies between the shoulder 301 and a removable plate 302 fastened to the bracket, a nut 303 engaging a threaded portion of the stem 300 and serving to adjust the position of the roller 111 110 relative to the box rest. To the rod 107 is adjustably secured, as by a slot 107' and screw 108', an arm forming a stop 113 projecting beyond the bracket and above the plane of the box rest, and the spring 112 115 urges the stop 113 into position beneath the rod 105 when no box is in position. Under this condition the end of rod 105, which is normally practically flush with the lower surface of pad 88, strikes the stop 113 before the glue pad 88 has descended sufficiently to touch the rest, and full movement of the block 92 is permitted without further descent of the pad. When a box is in position on the rest, the roller will engage 120 the wall of the same just above the inner flange 46 which it will be remembered does not extend the full height of the box. Thus the stop 113 is kept out of alignment with the rod 105 and full descent of the glue pad 125 120

into the box is permitted. The slot and screw connection with the nut 303 enable the tension of spring 112 to be regulated, though the stop 113 be adjusted to different positions relative to the path of the box.

In applying labels to boxes it is desirable to produce an article having a finished appearance, one in which the label lies smoothly, and without air bubbles or wrinkles and one in which the label is accurately arranged with respect to the article to which it is attached. To this end the glue should be applied in definite places, and the label should be affixed so as to register as accurately as possible with the glued portion of the article. These objects are efficiently attained by supporting the glue pad on rods connected thereto at opposite sides of the pad, as by supporting and guiding rods 114 attached to each end of the cross-head 91, and guided in elongated bearings 115 and 116 on the bed plate and stand, respectively. Reciprocatory motion is communicated to the glue pad through the cross-head by a cam 117 secured to shaft 23, and engaging a roller 118 on a tie bar 119 connecting the rods 114. Glue having been applied to the inside of the box, the glued box is then moved to label-applying position. Here it arrives beneath the label magazine 120 provided with spring fingers 121 to retain a pile of labels, as described in the prior patent hereinbefore referred to. In the present embodiment, however, the springs extend below the rigid walls of the label magazine in order to enter the box without interference from said walls. The label magazine is preferably supported and moved into label-applying position by means of the cross head 91 to which it is adjustably fixed, although it will be apparent that any other efficient means of bringing the box and the label holder into label-applying position may be provided. In the present embodiment, as the cross head reciprocates the label magazine moves back and forth toward the box, and in its lowered position the label carrying fingers enter the box and position the bottom label as closely adjacent the glued surface of the box to be labeled as the engaging fingers of the magazine will permit.

Ordinarily, the pile of labels will bulge outwardly at the bottom so that when the magazine descends the bottom label will be brought into contact with the glued surface of the box. However, in order to insure that the bottom label in the magazine shall contact with the glued surface of the box, means are provided for operating upon the labels to push the adjacent label from the magazine to the glued surface of the box and to press the same thereagainst. In the preferred embodiment a follower or hammer 98 is situated in position to be moved from and

against the labels in the magazine to strike the pile of labels when the magazine is in label-applying position, and thus push the bottom label from the magazine onto the box and press the same thereagainst. Preferably this hammer comprises a head 122 having an upstanding stem or rod 123 guided in a bracket 124 supported from the frame of the machine, said rod being toothed, providing a rack 125 adapted to be engaged at the proper time by a sliding dog and held in striking position. Means are provided for raising the hammer to striking position above the pile of labels in the magazine, comprising a block 126 slidable on the rod and a pivoted cam piece 127 co-operating with said block in certain positions to grip the rod. A connecting or operating rod 128 operated from a suitable part of the machine, as will hereinafter appear, is pivotally connected at 129 to an arm 130 fixed to the cam portion of the grip, and the parts are so disposed that when the connecting rod 128 is raised the rod 123 of the hammer is gripped and raised therewith. The rack having been raised to the extent of movement of the connecting rod, the dog engages the rack 125 on the rod and holds the hammer in elevated position when the grip is released upon the descent of the connecting rod. In order that the hammer may descend under other influence than gravity, a spring 131 is connected thereto at one end and to the bracket 124 at the other, in order to drive the hammer against the labels in the magazine. A sliding dog 132 is held on the bracket by means of a plate 133, and a spring 134 surrounding a stem 135 on the dog tends to force the latter toward the rack. Laterally disposed with respect to the dog is an anti-friction roller 136, in turn adapted to be engaged by a slidable cam 137 which, as it is moved one way or the other, either contacts the roller to withdraw the dog from the rack, or permits said dog to engage the teeth of the rack. As the magazine descends and reaches labeling position, a trip arm 138 thereon contacts with the slidable cam, causing the latter to move in a direction to withdraw the dog from the rack, permitting the hammer to descend under the influence of its spring. Preferably a cushioned contact is provided between the trip and the slidable cam, as by means of a spring buffer 139 on the slidable dog. As the magazine approximates the limit of its upward movement the trip arm engages an adjustable stop 140 upon the slidable cam and raises said cam, thus releasing the dog, which at the proper time springs into position to engage the rack. It will be observed, however, that the cam grip controlling the rise of the hammer is so arranged relative to the operation of the labeling device that said hammer will have been raised to strike the labels in the magazine.

ing position before the trip will operate to release the dog. It will be further observed that by reason of the free sliding engagement between the hammer and its elevating device, the hammer readily follows the descent of the labels in the magazine and is at all times raised to a proper striking distance from the topmost label. As the pile of labels in the magazine decreases in height, the hammer descends lower and lower into the magazine, and said hammer is provided with a sounder 141 adapted to contact with a bell 142 when the pile of labels has been materially decreased. Preferably the rod of the hammer is of non-circular cross section, so as to be accurately guided in its reciprocatory movements. The block 126 has quite a free sliding movement on the rod 123, and in order to keep the block in contact with the rod 123 at one side a light spring 143 is secured at one end to the block at the side of the bracket and at the other end to said bracket, this arrangement tending to prevent lost motion and causing the cam 127 to immediately pick up the hammer at the beginning of its upward movement.

It may here be noted that when the label is applied to the glued surface inside the box, any tendency of the box to follow the retreat of the label holder is prevented by the overhanging portions 47 of the flanges 44 and 45. The hammer mechanism, however, is well adapted to serve its purpose when labels are applied to the outside surface of a box, and when the flanges of the rests are omitted. Under such conditions any tendency of the box to follow the retreat of the label magazine, due to the sticking of the labels together, or any other cause, is prevented by longitudinally movable yielding, non-rotatable rods 144 carrying transversely adjustable box-engaging fingers or pins 145, stops, in the shape of adjustable nuts 145', and interposed springs 146 tending to urge the fingers from the magazine. When the magazine descends to apply a label outside the box, the fingers 145 contact at diagonally opposite points with the surface of the box before the application of the label and tend to press the box away from the label holder. In the present instance, the rods 144 are square in section and carried in diagonally opposite portions of the walls of the label magazine, and the fingers 145 project from said rods in position to engage the corners of the box outside of or beneath the label to be applied.

146' indicates a bearing bracket fixed to the frame of the machine and supporting a rock lever 147 pivotally connected at one end to the connecting rod 128 of the cam grip which operates the hammer, the other end of said lever having an anti-friction roller 148 co-operating with a cam 149 on the shaft 23, the cam 149 being suitably shaped

to cause the movement of the grip at the proper times in the operation of the machine.

The labels having been applied to the boxes in the manner hereinbefore explained, the carrier is again moved and the boxes next assume position beneath a pressing device, by means of which the label is firmly pressed against the bottom of the box on the inside thereof. In the present embodiment three pressing stations are provided so that, as the labeled box travels toward stripping position three separate pressures are applied thereto in order to make the label firmly adhere to the bottom of the box and remove all air bubbles, wrinkles, etc. Inasmuch as all of the presses are similar in construction, but one of them will be specifically described. Mounted on the platform is a bracket 150 having a horizontal arm 151 projecting over the path of the box rests and having a guiding opening 152 in alignment with the position assumed by the box rest when in stationary position therebeneath. Inasmuch as the labeled boxes in the present embodiment are rectangular in form, the guiding opening is of such a character, in this instance rectangular, as to maintain the relative position of a rectangular press head and a box, so that as the press moves toward and from the box it will always remain in accurate alignment therewith.

The numeral 153 indicates a press head preferably having a rubber pressing face 154 and provided with a tubular stem 155 terminating in an upper shoulder 156 between which and the bracket arm 151 is located a relatively strong spring 157. A loose pin 158 is adapted to play longitudinally inside the stem, and interposed between the press head and the end of said loose pin is a relatively light or weak spring 159. Pivoted to an upstanding portion of the bracket is a rock lever 160 having at one end an adjustable pin 161 adapted to contact the end of the loose pin, the other end of said rock lever being adapted to be engaged by a reciprocatory plunger 162 feathered in an elongated bearing 163 of the fixed platform 6 and provided with an anti-friction roller 164 adapted to engage the rock lever. Reciprocatory movement is communicated to said plunger by means of a cam 165 having a plurality of operating faces, in this instance three, so that one rotation of said cam will cause the plunger to rise and fall three separate times. When the plunger rises the pin contacting the head of the loose pin compresses the weak spring, and the character of the weak and loose springs is preferably such that the resistance of the weak spring before complete compression will overbalance that of the strong spring, whereupon the strong spring will also be compressed and the press head 130

will descend into the box and press the label against the bottom of the same, spreading the same out, and on account of the plurality of operating faces of the cam, patting the label. The plunger is provided with a collar 166 carrying three arms 167, each provided with an anti-friction roller 164 adapted to contact respectively with the lower faces of the rock levers of the several 10 presses for the purpose of simultaneously operating said presses.

Under normal operating conditions the pins 161 are always in contact with the loose pins 158, and the rollers 164 with the rock 15 levers 160. As the plunger 162 rises, the rock levers 160 encounter a yielding resistance, and as the lighter springs 159 are not completely compressed during the pressing of the labels, they offer at all times an 20 elastic resistance between the press heads and the rock levers 160, preventing undue strain and possible fracture of the rock levers 160, under abnormal conditions.

It will be understood that the presses are 25 located at such points adjacent the path of the boxes where the boxes are temporarily stationary, in the present instance one press being located at the immediately subsequent stationary position following the label af- 30 fixing position, and two others spaced apart to provide idle stations where the boxes may be readily inspected or manipulated.

The labeled box having been subjected to the action of the several presses hereinbefore 35 mentioned, is next moved into position in front of an ejecting mechanism comprising a bracket 168 mounted upon the fixed central platform 6, in which bracket is guided a movable ejector comprising a reciproca- 40 tory rod 169 having a depending portion or finger 170 moving in a path to intersect that of the boxes and adapted to enter the chamber of the box rest above the inner flange or stop 46. The path of movement of the 45 ejector rod not being at right angles to the axis of the operating rock shaft 58, it is operatively joined thereto through the instrumentality of a connecting rod 171, universal joints 172 and 173, and an arm 174 secured 50 to the rock shaft 58.

Referring to the operation of the glue-applying roller 87, it is deemed preferable to move this roller back and forth over the glue pad for each gluing operation of said 55 pad, and in order to efficiently accomplish this operation the roller 87 is journaled in a longitudinal frame 175, adapted to reciprocate in the guides 85 which extend between the guide rods 114 of the cross head 60 below said head and across the path of the box rests. The roller 87 thus moves in line with the space between the rods 114 and glue is applied to the pad uniformly, there 65 being practically no tendency of either the pad or the roller to rock on their supports,

which might result in a greater thickness of glue on one side of the pad than on the other. The frame 175 is operated through a connecting rod 176 pivotally joined to the frame at one end, the other end of the rod 70 being pivotally connected to the end of one arm of a rock lever 177 journaled in a fixed bracket 178, the other arm of the lever 177 being adjustably pivotally connected to one end of a connecting rod 179. The opposite 75 end of the rod 179 is pivotally connected to an arm 180 of a rock shaft 181 journaled in bearings fastened to the machine frame, and an anti-friction roller 182 projects laterally from the arm 180 into a groove 183 80 of a cam 184 fastened to the shaft 23. The groove of this cam is so designed that for each rotation of the shaft 23 a complete positive reciprocation of the roller 87 will be effected, with an intervening period of 85 rest when said roller is being supplied with glue from the rollers of the reservoir.

The details of the mechanism for conveying the boxes to position to be operated on by the picker, and of the devices for feeding glue to the supply roller 87 have not been specifically described other than as hereinbefore set forth, as they are generally similar to those in the prior patent referred to. It may be noted, however, that 90 in this embodiment the conveyer belt is continuously driven by the chain 32, and the feed roller of the glue reservoir by the chain 31 engaging a sprocket wheel 185 of a shaft 186, a clutch 187 being interposed for the 95 purpose of cutting out the glue feeding rollers when desired.

The operation of the machine will be apparent from the foregoing description, and further explanation thereof would appear 100 unnecessary. It will be observed that by the construction herein described are accomplished, among others, the objects hereinbefore set forth.

As many changes could be made in the 105 above construction and many apparently widely different embodiments of this invention could be made without departing from the scope thereof, it is intended that all matter contained in the above descrip- 110 tion or shown in the accompanying drawings shall be interpreted as illustrative and not in a limiting sense. It is also to be understood that the language used in the following claims is intended to cover all of the 115 generic and specific features of the invention herein described, and all statements of the scope of the invention which, as a matter of language, might be said to fall therebetween.

Having described my invention, what I claim as new and desire to secure by Letters Patent is:

1. In an apparatus of the character described, in combination, a box rest, means 120

- adapted to feed a box to and position the same on the rest, and a pivoted latch adapted to be interposed alongside the box in the path of feed to retain the box on the rest.
- 5 2. In an apparatus of the character described, in combination, a presser pad, means adapted to move the same to press an article comprising a spring, and a resilient device positioned to oppose said movement.
- 10 3. In an apparatus of the character described, in combination, a presser pad, resilient means for supporting the pad, and means for moving the pad in opposition to the resilient means comprising a relatively weak spring.
- 15 4. In an apparatus of the character described, in combination, a fixed support, a movable presser pad having a non-rotary shaft slidably mounted on the support, a relatively stiff spring surrounding the shaft and adapted to move the pad in one direction, operating means comprising a pin longitudinally movable in the shaft adapted to move in the opposite direction, and a relatively weak spring interposed between said pin and the pad.
- 20 5. In an apparatus of the character described, in combination, a press, a relatively strong spring adapted to resiliently support the same, and means to move the press against the resistance of said spring, comprising a relatively weak spring.
- 25 6. In an apparatus of the character described, in combination, a press, a relatively strong spring adapted to resiliently support the same, means to move the press against the resistance of said spring, comprising a relatively weak spring, and a loose pin adapted to contact the latter spring.
- 30 7. In an apparatus of the character described, in combination, a press, a relatively strong spring adapted to resiliently support the same, means to move the press against the resistance of said spring, comprising a relatively weak spring, a loose pin adapted to contact the latter spring, and a rock lever adapted to contact said pin.
- 35 8. In an apparatus of the character described, in combination, a press, a relatively strong spring adapted to resiliently support the same, means to move the press against the resistance of said spring, comprising a relatively weak spring, a loose pin adapted to contact the latter spring, and a rock lever having an adjustable pin adapted to contact said loose pin.
- 40 9. In an apparatus of the character described, in combination, a press, a relatively strong spring adapted to resiliently support the same, means to move the press against the resistance of said spring, comprising a relatively weak spring, a loose pin adapted to contact the latter spring, a rock lever, one end of which is adapted to contact said pin, a plunger adapted to contact the other end of said lever, and cam means to reciprocate said plunger a plurality of times for each rotation of the cam.
- 45 10. In an apparatus of the character described, in combination, a press, a relatively strong spring adapted to resiliently support the same, means to move the press against the resistance of said spring, comprising a relatively weak spring, a loose pin adapted to contact the latter spring, a rock lever, one end of which is adapted to contact said pin, a plunger adapted to contact the other end of said lever, and cam means to reciprocate said plunger a plurality of times for each rotation of the cam.
- 50 11. In an apparatus of the character described, in combination, a press, a relatively strong spring adapted to resiliently support the same, means to move the press against the resistance of said spring, comprising a relatively weak spring, a loose pin adapted to contact the latter spring, a rock lever, one end of which is adapted to contact said pin, a non-rotatable plunger adapted to contact the other end of said lever, and means to reciprocate said plunger.
- 55 12. In an apparatus of the character described, in combination, a support, a box feeding device reciprocatorily mounted on the support, comprising a picker bar, a picker finger pivoted to the bar, and a friction clutch device between the picker finger and the bar adapted to yieldingly oppose movement of the finger relative to the bar in one direction.
- 60 13. In an apparatus of the character described, in combination, a support, a box feeding device reciprocatorily mounted on the support, comprising a picker bar, a picker finger pivoted to the bar, a friction clutch device between the picker finger and the bar adapted to yieldingly oppose movement of the finger relative to the bar in one direction, and a spring connected to the bar and finger to yieldingly oppose relative movement of the finger in the opposite direction.
- 65 14. In an apparatus of the character described, in combination, a picker comprising a movable support, a picker finger, means yieldingly connecting the support and finger, comprising co-operating clutch elements on said parts, and means pressing the elements together and permitting the finger to yield in either direction relative to the support.
- 70 15. In an apparatus of the character described, in combination, a picker comprising a movable support, a friction tooth thereon, a picker finger pivoted to the support, and having a depression to engage the said tooth, and a spring adapted to press the support and finger toward each other.
- 75 16. In an apparatus of the character described, in combination, a picker comprising a movable support, a friction tooth

thereon, a picker finger pivoted to the support, and having a depression to engage the said tooth, a pin on said support passing through an opening in the finger, and a 5 spring surrounding said pin and adapted to press the support and finger toward each other.

17. In an apparatus of the character described, in combination, a magazine adapted to support a pile of labels in delivery position, means whereby boxes are brought into labeling position relative to the magazine, a hammer, means to successively move the hammer into striking position relative 10 to the pile, means to retain the hammer in such position, means to release the hammer when the boxes assume labeling position, and means comprising a spring to cause the hammer to strike the pile.

18. In an apparatus of the character described, in combination, a magazine adapted to support a label, means adapted to support a box, means to move the magazine to carry the label into label applying position 15 relative to the box, and resiliently operated means to push the label from the magazine onto the box.

19. In an apparatus of the character described, in combination, a support adapted 20 to carry a box, a label holder comprising spring label supporting fingers means to move said fingers into and out of the box, a hammer, and means to operate the hammer to press the label against the inside of the 25 box.

20. In an apparatus of the character described, in combination, a series of movable box rests, each having projections to position the boxes thereon and an intervening 30 opening permitting the boxes to be slid onto the rests, relatively movable box retaining means carried by each rest, and means adapted to cause the retaining means to open and close the opening during the movement of the rests.

21. In an apparatus of the character described, in combination, a series of movable box rests, means thereon to position boxes comprising relatively movable box retainers, 35 a fixed cam track adjacent the path of the rests adapted to move the retainers into and out of retaining position, and means adapted to move boxes onto said rests when said retainers are out of retaining position.

22. In an apparatus of the character described, in combination, a rotary horizontal table, a series of box rests thereon, each comprising projections to position a box thereon and an intervening opening, relatively movable box retaining means carried by each rest, and a cam track adapted to move the retainer to close or open the opening at certain positions of the rest.

23. In an apparatus of the character described, in combination, box rests movable

in an endless path, a plurality of resiliently supported pressers adjacent the path of movement, and means to cause the pressers to simultaneously move toward or away from the rests.

24. In an apparatus of the character described, in combination, a box rest, a presser resiliently suspended adjacent thereto, and means to yieldingly press the presser against a box on the rest.

25. In an apparatus of the character described, in combination, a box rest, a plurality of pressers adjacent thereto, operating means for each presser comprising a rock lever, and a single means for operating each lever.

26. In an apparatus of the character described, in combination, a rotary horizontal table, a series of box rests carried thereby, a stationary platform, pressers supported on the platform adjacent different points in the path of the rests, a shaft guided by the platform, means for reciprocating said shaft, and rock levers adapted to communicate the movement of the shaft to the pressers.

27. In an apparatus of the character described, in combination, a rest having members to guide and position a box thereon, the members providing portions projecting over 95 the flange of the box to limit movement on the rest, a label holder, means adapted to cause relative movement between the holder and rest toward and from each other to position a label inside the box, and means 100 to affix a label inside the box.

28. In an apparatus of the character described, in combination, a box rest comprising a chamber, means adapted to move a box into said chamber, and an elastically mounted roller adapted to maintain the box and chamber in alinement as the box moves.

29. In an apparatus of the character described, in combination, a horizontal box rest having spaced upwardly projecting 110 flanges comprising portions adapted to overhang a box on the rest, means adapted to move a box onto the rest between the flanges, a roller in the path of the box moving to the rest, and a spring to hold the roller in 115 the path and permit it to rise as the box passes.

30. In an apparatus of the character described, in combination, a box support adapted to freely support a box, a label holder, 120 means for applying glue to the inner surface of a box on the support, means to move the label holder to press a label on the glued surface of the box, and means to prevent the box following the retreat of the label holder.

31. In an apparatus of the character described, in combination, means for supporting a plurality of boxes, a plurality of separate pressers, means to move one of the assemblage of elements just mentioned into 130

alinement with the other assemblage, means to glue labels to the boxes, and means comprising a single cam having a plurality of operative faces adapted to bring the pressers 5 and the boxes together to press the labels against the boxes.

32. In an apparatus of the character described, in combination, means for supporting a plurality of boxes, a plurality of separate pressers, means to move one of the assemblage of elements just mentioned into alinement with the other assemblage, means to glue labels to the inside of the boxes, and means comprising a single cam having a 15 plurality of operative faces adapted to bring the pressers and the boxes together to press the labels against the inside of the boxes.

33. In an apparatus of the character described, in combination, means adapted to support and move a plurality of boxes, comprising relatively stationary means to retain the boxes in position on the support, means adapted to feed boxes onto said support into engagement with the stationary 25 retaining means, means adapted to move into position relative to the retaining means and keep the boxes on the support, and means adapted to move the keeper into and out of retaining position.

34. In an apparatus of the character described, in combination, a movable box support comprising relatively stationary box guiding and retaining means, means adapted to supply boxes to a certain position, 35 means to feed a box from the supply means to the support, relatively movable means to retain the box on the support, means to move the box support to another position, and means to keep the retaining means in 40 retaining position during the movement of the support.

35. In an apparatus of the character described, in combination, a movable box support comprising relatively stationary box guiding and retaining means, means adapted to supply boxes to a certain position, means to feed a box from the supply means to the support, relatively movable means to retain the box on the support, means to 45 move the box support to another position, means to keep the retaining means in retaining position during the movement of the support, means to strip the box from the support, and means to move the retaining 50 means out of retaining position when the box reaches the stripping means.

36. In an apparatus of the character described, in combination, a rotary table, a plurality of box rests carried thereby, means to rotate the table step by step, box feeding mechanism adjacent said table, a fixed cam, and means co-operating with the cam and carried by the table to retain the boxes on the support as the support moves.

37. In an apparatus of the character de-

scribed, in combination, a rotary table, a plurality of box rests carried thereby, means to rotate the table step by step, box feeding mechanism adjacent said table, a fixed cam, box retaining means comprising a movable 70 element, and means co-operating with the cam to move the element into and out of retaining position.

38. In an apparatus of the character described, in combination, a table, a series of 75 box rests supported thereby, box feeding mechanism, box labeling mechanism comprising means adapted to affix a label to the inside of a box, box stripping mechanism, and movable means adapted to engage the 80 boxes to retain them on the rests during the labeling operations, and permit their discharge by the stripping mechanism after the labeling operations.

39. In an apparatus of the character described, in combination, guideways arranged at angles to each other and along which boxes are to be moved, and means for moving boxes along the guideways, and a yielding stop between the walls of one guideway, and adjacent the intersection of said guideways.

40. In an apparatus of the character described, in combination, a rotary carrier, means thereon adapted to position boxes to 95 move in an endless horizontal path comprising spaced projections between which the boxes are received, oppositely disposed projections having portions adapted to overhang the edges of the boxes, means adapted 100 to rotate the carrier step by step, means opposite positions of rest of the positioning means adapted, respectively, to supply boxes to the positioning means, to assemble labels with the boxes on the positioning means, to 105 provide one of the assembled elements with adhesive, and to press the assembled boxes and labels.

41. In an apparatus of the character described, in combination, a rotary carrier, 110 means thereon adapted to position boxes to move in an endless horizontal path comprising spaced projections between which the boxes are received, oppositely disposed projections having portions adapted to overhang the edges of the boxes, one of said projections being lower than the upper edge of the box, means adapted to rotate the carrier 115 step by step, means opposite positions of rest of the positioning means adapted, respectively, to supply boxes to the positioning means, to assemble labels with the boxes on the positioning means, to provide one of the assembled elements with adhesive, and to press the assembled boxes and labels.

42. In an apparatus of the character described, in combination, a rotary carrier, means thereon adapted to position boxes to move in an endless horizontal path comprising spaced projections between which 120

the boxes are received, means adapted to rotate the carrier step by step, means opposite a position of rest of the positioning means adapted to slide boxes between the 5 spaced projections, means adapted to intersect the sliding path of the boxes and retain the boxes in position, to assemble labels with the boxes on the positioning means, to provide one of the assembled elements with 10 adhesive, and to press the assembled boxes and labels.

43. In an apparatus of the character described, in combination, a rotary carrier, means thereon adapted to position boxes to 15 move in an endless horizontal path comprising spaced projections between which the boxes are received, means adapted to rotate the carrier step by step, means opposite positions of rest of the positioning means 20 adapted, respectively, to slide boxes between the spaced projections, means pivoted on the carrier adapted to intersect the sliding path of the boxes and retain the boxes in position, a cam track engaged by the retaining 25 means, means to assemble labels with the boxes on the positioning means, to provide one of the assembled elements with adhesive, and to press the assembled boxes and labels.

44. In an apparatus of the character described, in combination, a rotary carrier, means thereon adapted to position boxes to 30 move in an endless horizontal path comprising spaced projections between which the boxes are received, means adapted to rotate 35 the carrier step by step, a guideway opposite a position of rest of said positioning means, a box conveyer adapted to feed boxes into position opposite the guideway, yielding means adapted to preserve the alinement of 40 the boxes with the guideway and permit passage of boxes into said guideway, means to feed boxes through the guideway to the positioning means, means to assemble labels with the boxes on the positioning means, to 45 provide one of the assembled elements with adhesive, and to press the assembled boxes and labels.

45. In an apparatus of the character described, in combination, a carrier, means to 50 rotate the same step by step, means comprising keepers on the carrier adapted to position boxes to move in an endless path, means respectively opposite different positions of rest of the positioning means adapted to 55 supply boxes to the positioning means, to perform a labeling operation on the boxes on the positioning means, and to eject the labeled boxes from the positioning means, and means adapted to dispose the keepers 60 out of box engaging position when boxes are to be supplied or ejected from the positioning means, and to dispose the keepers in box engaging position during said labeling operations.

46. In an apparatus of the character de-

scribed, in combination, a carrier, means to rotate the same step by step, means comprising keepers on the carrier adapted to position boxes to move in an endless path, means respectively opposite different positions of rest of the positioning means adapted to supply boxes to the positioning means, to perform a labeling operation on the boxes on the positioning means, and to eject the labeled boxes from the positioning means, 75 and cam means adapted to dispose the keepers out of box engaging position when boxes are to be supplied or ejected from the positioning means, and to dispose the keepers in box engaging position during said labeling 80 operations.

47. In an apparatus of the character described, in combination, a carrier, means to rotate the same step by step, means comprising keepers on the carrier adapted to position boxes to move in an endless path, means respectively opposite different positions of rest of the positioning means adapted to supply boxes to the positioning means, to perform a labeling operation on the boxes 90 on the positioning means, and to eject the labeled boxes from the positioning means, and means comprising a fixed cam track adapted to dispose the keepers out of box engaging position when boxes are to be supplied or ejected from the positioning means, and to dispose the keepers in box engaging 95 position during said labeling operations.

48. In an apparatus of the character described, in combination, a carrier, means to 100 rotate the same step by step, means comprising keepers on the carrier adapted to position boxes to move in an endless path, means respectively opposite different positions of rest of the positioning means adapted to supply boxes to the positioning means, to perform a labeling operation on the boxes on the positioning means and to eject the labeled boxes from the positioning means, and means comprising a fixed cam track having 105 inclined portions adapted to dispose the keepers out of box engaging position when boxes are to be supplied or ejected from the positioning means, and to dispose the keepers in box engaging position during said labeling 110 operations.

49. In an apparatus of the character described, in combination, a horizontal table, box rests disposed thereon in an endless series, each rest comprising a laterally open 115 chamber, keepers, one for each rest, means adapted to move the keepers into and out of position opposite the openings, and means adapted to yieldingly maintain the keepers in the position to which moved.

50. In an apparatus of the character described, in combination, a support, means thereon adapted to position boxes to move in a predetermined path, means adapted to move the support step by step, means oppo- 130

- site positions of rest of the positioning means adapted to supply boxes to the positioning means, means adapted to assemble labels with the boxes on the positioning 5 means, means adapted to provide one of the elements to be assembled with glue, comprising a glue carrier, means adapted to cause the carrier to apply glue to an article when in position on the support, and movable means to prevent the application of glue to the support when an article is not in gluing position thereon.
51. In an apparatus of the character described, in combination, a support, means thereon adapted to position boxes to move in a predetermined path, means adapted to move the support step by step, means opposite positions of rest of the positioning means adapted to supply boxes to the positioning 15 means, means adapted to assemble labels with the boxes on the positioning means, means adapted to provide one of the elements to be assembled with glue, comprising a glue carrier, means adapted to move the glue carrier toward the support, and means adapted to permit the full movement of the glue carrier moving means and prevent the full movement of the glue carrier.
52. In an apparatus of the character described, in combination, a support, means thereon adapted to position boxes to move in a predetermined path, means adapted to move the support step by step, means opposite 20 positions of rest of the positioning means adapted to supply boxes to the positioning means, means adapted to assemble labels with the boxes on the positioning means, means adapted to provide one of the elements to be assembled with glue, a glue pad support, a glue pad movably mounted on the pad support, means to reciprocate the pad toward and from the box in position to be glued, a detent connected to the pad, a movable stop adapted to prevent the pad contacting the box support, and means adapted to automatically maintain the stop 25 in the line of movement of the detent when no box is in gluing position on the box support.
55. In an apparatus of the character described, in combination, a support, means thereon adapted to position boxes to move in a predetermined path, means adapted to move the support step by step, means opposite positions of rest of the positioning means adapted to supply boxes to the positioning 30 means, means adapted to assemble labels with the boxes on the positioning means, means adapted to provide one of the elements to be assembled with glue, a glue pad support, a glue pad movably mounted on the pad support, means to reciprocate the pad toward and from the box in position to be glued, a detent connected to the pad, a movable stop adapted to prevent the pad contacting the box support, means adapted to automatically maintain the stop 35 in the line of movement of the detent when no box is in gluing position on the box support, and cam means adapted to contact a box and remove the stop from the line of movement of the detent.
56. In an apparatus of the character described, in combination, a support, means thereon adapted to position boxes to move in a predetermined path, means adapted to move the support step by step, means opposite positions of rest of the positioning means adapted to supply boxes to the positioning 40 means, means adapted to assemble labels with the boxes on the positioning means, means adapted to provide one of the elements to be assembled with glue, comprising a glue carrier, means adapted to move the glue carrier toward the support, and means governed by the box to be glued to control the movement of the glue carrier.
53. In an apparatus of the character described, in combination, a support, means thereon adapted to position boxes to move in a predetermined path, means adapted to move the support step by step, means opposite 45 positions of rest of the positioning means adapted to supply boxes to the positioning means, means adapted to assemble labels with the boxes on the positioning means, means adapted to provide one of the elements to be assembled with glue, a glue pad support, means to reciprocate the glue pad support toward and from the box support, a glue pad movably mounted on the pad support, a detent connected to said pad, and a stop adapted to move into and out of the path of the detent to control the extent 50 of movement of the pad.
54. In an apparatus of the character described, in combination, a support, means thereon adapted to position boxes to move in a predetermined path, means adapted to move the support step by step, means opposite positions of rest of the positioning means adapted to supply boxes to the positioning 55 means, means adapted to assemble labels with the boxes on the positioning means, means adapted to provide one of the elements to be assembled with glue, a glue carrier adapted to enter the boxes and apply glue to the inner wall thereof, and means adapted to limit the movement of the glue carrier to a point above the position assumed by a box when no box is in gluing position on the support.
57. In an apparatus of the character described, in combination, a support, means thereon adapted to position boxes to move in a predetermined path, means adapted to move the support step by step, means opposite positions of rest of the positioning means adapted to supply boxes to the positioning 60 means, means adapted to assemble labels with the boxes on the positioning means, means adapted to provide one of the elements to be assembled with glue, a glue carrier adapted to enter the boxes and apply glue to the inner wall thereof, and means adapted to limit the movement of the glue carrier to a point above the position assumed by a box when no box is in gluing position on the support.

- tioning means, means adapted to assemble labels with the boxes on the positioning means, means adapted to provide one of the elements to be assembled with glue, a glue carrier adapted to enter the boxes and apply glue to the inner wall thereof, a detent carried thereby, a stationary support, a stop carried thereby, a cam connected to the stop, and means to yieldingly hold the cam in the path of the boxes on the support and the stop in the path of the detent.
58. In an apparatus of the character described, in combination, a carrier, means adapted to intermittently move the carrier, means on the carrier adapted to retain open boxes in relatively stationary position to present the open end outward, a conveyer belt for boxes, a reciprocatory picker adapted to slide boxes from said belt to said retaining means, and means adapted to adhesively affix a label to the inside walls of the boxes while the latter are held by said retaining means.
59. In an apparatus of the character described, in combination, a carrier, means adapted to intermittently move the carrier, means on the carrier adapted to retain open boxes in relatively stationary position to present the open end outward, a conveyer belt for boxes, a reciprocatory picker adapted to slide boxes from said belt to said retaining means, means adapted to adhesively affix a label to the inside walls of the boxes while the latter are held by said retaining means, comprising a label magazine having label supporting fingers adapted to enter the boxes, means adapted to move said fingers into and out of the boxes, and means adapted to remove the boxes from said retaining means.
60. In an apparatus of the character described, in combination, guideways arranged at angles to each other and along with boxes which are to be moved, means for moving boxes along the guideways, and a yielding roller in one guideway, the plane of rotation of said roller being transverse to the direction of movement of the box in the other guideway.
61. In an apparatus of the character described, in combination, a carrier, means adapted to move said carrier, means on said carrier adapted to retain a box in relatively stationary position to present the open end outward, comprising a movable keeper, means adapted to adhesively affix a label to the inside wall of said box, and means adapted to move boxes onto said retaining means.
62. In an apparatus of the character described, in combination, a carrier, means adapted to move said carrier, means on said carrier adapted to retain a box in relatively stationary position to present the open end outward, comprising a movable keeper, means adapted to adhesively affix a label to the inside wall of said box, comprising a glue carrier adapted to move toward and from the inside wall to be glued, and means adapted to move boxes onto said retaining means.
63. In an apparatus of the character described, in combination, a carrier, means adapted to move said carrier, means on said carrier adapted to retain a box in relatively stationary position to present the open end outward, comprising a movable keeper, means adapted to adhesively affix a label to the inside wall of said box, comprising a glue carrier adapted to move toward and from the inside wall to be glued, a label presser pad, resilient means for supporting said pad, means for moving said pad in opposition to said resilient means comprising a relatively weak spring, and means adapted to move boxes onto said retaining means.
64. In the apparatus of the character described, in combination, a carrier, means adapted to move said carrier, means on said carrier adapted to retain a box in relatively stationary position to present the open end outward, comprising a movable keeper, means adapted to adhesively affix a label to the inside wall of said box, and means adapted to move boxes onto said retaining means, comprising a picker bar, a picker finger pivoted to said bar, and a friction clutch device between the picker finger and the bar adapted to yieldingly oppose movement of the finger relative to the bar in one direction.
65. In an apparatus of the character described, in combination, a carrier, means adapted to move said carrier, means on said carrier adapted to retain a box in relatively stationary position to present the open end outward, comprising a movable keeper, means adapted to adhesively affix a label to the inside wall of said box, comprising a glue carrier adapted to move toward and from the inside wall to be glued, a label presser pad, resilient means for supporting said pad, means for moving said pad in opposition to said resilient means comprising a relatively weak spring, means adapted to move boxes onto said retaining means, comprising a picker bar, a picker finger pivoted to said bar, and a friction clutch device between the picker finger and the bar adapted to yieldingly oppose movement of the finger relative to the bar in one direction.
66. In an apparatus of the character described, in combination, a carrier, means adapted to move said carrier, means on said carrier adapted to retain a box in relatively stationary position to present the open end outward, comprising a movable keeper, means adapted to adhesively affix a label to the inside wall of said box, comprising a magazine adapted to support a pile of labels and permit them to deliver therefrom, a hammer, means adapted to move boxes onto said retaining means.

cause said hammer to strike the pile and thereby press a label against the inside wall of the box, and means adapted to move boxes onto said retaining means.

- 5 67. In an apparatus of the character described, in combination, a horizontal table, box rests disposed thereon in an endless series, each rest comprising a laterally open chamber, keepers, one for each rest, means adapted to move the keepers into and out of position opposite said openings, means adapted to adhesively affix labels to the inside walls of boxes on said rests comprising

a label magazine, means to move said magazine into and out of a box on one of said 15 rests, a hammer, means adapted to cause said hammer to strike said pile and thereby press a label against a box, and means adapted to move boxes onto said rests.

In testimony whereof I affix my signature, 20 in the presence of two witnesses.

LYNDON CONSTANTINE PALMER.
